FAUCET FITTING

Frederick David Chapman, Chicago, Ill., assignor to The Murray Corporation of America, Pittsburgh, Pa., a corporation of Delaware

Continuation of design applications Ser. Nos. 59,061 and 59,062, Jan. 15, 1960. This application May 9, 1961, Ser. No. 65,369

Term of patent 14 years

(Cl. D91—3)

Fig. 1.

Fig. 2.

Fig. 3.

Fig. 4.

Fig. 5.

Fig. 6.

Fig. 7.

Fig. 8.

FIG. 1 is a perspective view of a faucet fitting embodying my new design.

FIG. 2 is the side elevational view thereof;

FIG. 3 is a front elevational view thereof; and

FIG. 4 is a top plan view thereof.

FIG. 5 is a perspective view of a modified form of the faucet fitting shown in FIG. 1.

FIG. 6 is a front elevational view thereof;

FIG. 7 is a side elevational view thereof; and

FIG. 8 is a top plan view thereof.

The dominant features of my design reside in the portion shown in full lines.

This is a continuation of my prior applications Serial Nos. D. 59,061 and D. 59,062, both filed on January 15, 1960.

I claim:

The ornamental design for a faucet fitting, as shown and described.
